CLOSURE

Charles Mackintosh, Los Angeles, Calif.

Application March 29, 1944, Serial No. 528,598

24 Claims. (Cl. 160—34)

This invention relates to closures and more particularly to collapsible closures adapted for use in connection with large openings such as doorways for aircraft hangers, garages, factories, mills, assembly plants, shops, or other building structures.

The provision of closures for the large openings of this type of structure, which may be readily moved to and from effective closing position and yet be sufficiently strong to withstand wind loads, has presented a difficult problem. Prior proposals looking toward a satisfactory solution have generally involved one or the other of two types of door constructions.

The first type includes a rolling door resting on rails and adapted to be moved bodily to the side of the opening. Such devices have not been entirely satisfactory, being attended by numerous disadvantages not the least of which is the waste of space necessary to accommodate this type of door when it is in opened position.

The door of the second general type now in use is supported by truss structures extending across the building above the opening. These doors require extensive and costly superstructures with adequate clearances and sturdy enough to withstand the force of the wind blowing against the closure structure when the door is in completely closed position. Under these conditions the door acts as a beam to the top of the structure, and the entire surface of the door being solid, the total pressure of the wind against it is very great and the door and bracing structure must be correspondingly strong to resist this pressure. A few attempts have been made to provide vertically moving doors which are adapted to be received in a recess in the ground but these have also been solid doors subject to wind pressure and the problems of providing a strongly braced cantilever door structure arises.

By means of the present invention, however, these difficulties have been obviated and many advantages of construction, operation, and utility have been attained. In its preferred embodiments the invention contemplates the provision of a novel closure system including a multiplicity of parallel interchangeable panels supported during opening and closing movement in horizontal positions so that wind resistance is reduced to a minimum. The panels are preferably supported at their ends upon vertical columns which may be retracted into the ground and projected therefrom during opening and closing movement. The panels themselves, however, are adapted to be automatically disconnected from the columns one

by one as the latter are retracted, and to stack themselves in a relatively shallow trench provided at the threshold of the opening, and then to be re-attached to the columns as they rise to closing position. When the closure has risen nearly to its fully closed position, the upper ends of the column are guided into engagement with the overhead structure in such a way that the columns are in true vertical position and the door, even under full wind load throughout its area, is provided with adequate lateral support by the structure at the top of the columns.

When thus secured the several panels may be swung or rotated about a horizontal axis to vertical positions, whereby the horizontal side edges of adjacent panels come together to form a solid closure. One of the features of the invention is the provision of novel locking supports adapted to successively seize the superposed panels when the structure rises, and then rotate them to closed position when desired. The uppermost panel forms a floor at the threshold when the closure structure is collapsed, and the bottom panel of any set is preferably non-rotatable and forms a floor when the structure is raised to closed position. The floor panel may act as a girder keeping the tops of the columns in line.

The novel mutually interlocking devices on the columns and on the individual panels are so constructed and arranged that the weight of the superposed panels retains the parts carried by the panel ends in retracted positions substantially within the lateral confines of the panels, but as soon as the panel next above is lifted by the rising columns one or more connecting elements are projected from the panel ends into operative relationship with the cooperating receiving elements on the rising columns, and when a given panel is lifted from contact with the one next below, additional devices are projected toward the column carried mechanism to lock the panel securely thereto.

The closure provided by the present invention is adaptable to any size and shape of opening; a plurality of columns may be used which divide the groups of panels into sections or bays. In fact, the larger the opening to be controlled the more economical the present closure will be as compared with other existing types.

Other objects and features of novelty, including operating devices and anti-frictional guiding means, will be apparent from the following specification when read in connection with the accompanying drawings in which certain embodied

ments of the invention are illustrated by way of example.

In the drawings:

Figure 1 is a perspective view of one end of an aircraft hangar showing a closure installation embodying the principles of the invention;

Figure 2 is a partial view of the retractable closure showing the panels themselves in open position and illustrating one means of raising the closure;

Figure 3, 4, and 5 are transverse vertical sectional views through the closure and threshold trench illustrating the manner of successively raising the panels from the trench to vertically spaced positions by the supporting columns;

Figures 6, 7, 8, and 9 are detailed views in vertical section adjacent the bottom of the trench showing alternative arrangements for raising the supporting columns of the closure;

Figure 10 is an exploded view in perspective showing a guide bracket for the closure columns or posts;

Figure 11 is a view in horizontal section of one of the end columns of the closure and the edge of the door opening;

Figure 12 is a vertical sectional view through one of the locking supports carried by the columns between the adjacent ends of the panels of adjoining sections of the closure; the view being taken substantially on line 12—12 of Figure 13;

Figure 13 is a detailed view in elevation of the locking panel support on one side of a column;

Figure 14 is a horizontal sectional view taken on line 14—14 of Figure 13;

Figure 15 is a fragmentary view of one span of panels between two columns showing a portion of the locking and supporting mechanism and the cooperating actuating mechanism carried by the ends of the panels;

Figure 16 is a fragmentary perspective view of one end of one of the panels showing the projectible bolt and pin arrangement;

Figure 17 is a central longitudinal sectional view through the bolt mechanism, as taken on line 17—17 of Figure 19;

Figure 18 is a longitudinal sectional view taken on line 18—18 of Figure 19;

Figure 19 is a transverse vertical sectional view taken on line 19—19 of Figures 17 or 18;

Figure 20 is a similar view taken on line 20—20 of Figure 17; and

Figure 21 is a fragmentary perspective view of the upper end of a column showing a modification of the panel lock actuating mechanism for automatic separation at the end of the vertical travel of the closure.

In Figure 1 the building structure embodying the principles of the invention is indicated generally by the reference numeral 10, and may be an aircraft hangar or a similar large sized building. The building may have a trussed roof structure 11 supported upon the flat roofed wings 12 at either side of the building. The front wall of the roof structure is indicated at 13 and it will be seen that it spans the door opening 14 which is of extremely great width, say upwards of two hundred feet.

The closure system which exemplifies the present invention is designated generally by the reference numeral 15 and in the illustrated embodiment comprises a plurality of sections or bays 16 defined by the series of vertical columns 17, each of the sections 16 being comprised by a plurality of vertically spaced horizontally dis-

posed elongated interchangeable panel elements 20. In Figure 1 the closure is shown in closed position with the columns 17 projected upwardly from the ground to contact with the lintel formed by the lower edge of the front wall 13 of the roof structure. To open the closure 15 the columns are lowered into the ground until the upper ends thereof are either flush with the ground level or disposed beneath the same. During this retracting movement of the columns, the successive panels 20 of the sections are stripped therefrom and stacked one upon the other within a relatively shallow trench provided beneath the threshold of the door opening 14 as will be fully explained and described in connection with succeeding figures of the drawings.

Referring now to Figure 2 it will be seen that the columns 17 are preferably of I-section and are adapted to be received in the tubular casings 22 which provide sockets or recesses for the reception and guidance of the columns. These members 22 may be made of metal or concrete piping or other suitable material. As clearly shown in Figures 2 to 9, inclusive, the upper ends of the column receiving socket members 22 open into a trench 24 which may be walled with concrete to form a box-like structure 25. The bottom wall of the box 25 is provided around each of the members 22 with a low wall 26 which provides means for preventing water from draining into the sockets 22; however, in case moisture does collect in the bottoms of the socket members 22 any sort of pumping means such as that suggested diagrammatically at 27 may be employed to drain the water therefrom. At intervals along the trench 24 there may be disposed transverse bars or racks 28 which serve to support the panels 20 when the closure is in open or retracted position.

40 In Figure 3, the columns 17 have been withdrawn completely into the socket members 22 and all of the panels are stacked up in the trench, the uppermost panel 20B providing a sill or flooring element adapted to support the weight of man or vehicles passing through the opening or doorway. In Figure 4 of the drawings the columns 17 have been projected toward closed position, the uppermost panel 20B and several of the intermediate panels 20 having been engaged at the proper spaced intervals and raised from the pile. In Figure 5 the closure structure is shown raised to its fully closed position wherein the upper end of the columns 17 are received within the tapered sockets 29 in the superstructure 13. The lowermost panel 20A of the series which is spaced from the next higher panel 20 by a distance which is approximately one-half of the normal spacing between the panels, is disposed flush with the ground level and provides a cover for the trench 24. From the horizontal positions of the panels shown in Figure 5 they may be swung or rotated around a horizontal central axis somewhat in the manner of the familiar Venetian blind constructions so that the door or closure is completely closed against weather. The closed position of the panels is indicated by broken lines in the upper portion of Figure 5.

Mechanism for raising the columns 15 and thus moving the closure system to closed position may be selected from a wide variety of known lifting devices, but certain preferred forms devised in connection with the present invention are illustrated in Figures 2, 6, 7, 8 and 9 of the drawings. 70 65 In Figure 2 there is provided a drum or reel 30

70 moving the closure system to closed position may be selected from a wide variety of known lifting devices, but certain preferred forms devised in connection with the present invention are illustrated in Figures 2, 6, 7, 8 and 9 of the drawings. 75 In Figure 2 there is provided a drum or reel 30

rotatably mounted transversely of the trench 24 at the end thereof and adapted to be driven by means of the electric motor 31 through transmission means including a sprocket 32 mounted on the end of the motor shaft which is operatively connected by means of the drive chain 34 with a sprocket 33 carried by the reel. A plurality of cables 35 are wound upon sections of the reel or drum 30 and each cable is trained along the bottom of the trench and over suitable guides or pulleys and has its end secured to or operatively connected with the lower ends of the respective columns 17. For example, in Figure 6 a cable 35A passes over the pulley 36 rotatably mounted adjacent the wall 26 of the box 25, and the end of the cable 35A is secured as at 38 to the lower end of the column. In Figure 7, the cable 35B passes around a similar stationary pulley 36 and then around a pulley 39 rotatably carried by the end of the column 17, and then secured as at 40 to a stationary point adjacent the upper end of the well or socket member 22. In either embodiment, it will be readily seen that when the cables are wound up upon the drum 30, the columns 17 will be raised and conversely when the drum 30 is allowed to unwind, the columns 17 will be lowered and the panels deposited in the trench.

In the embodiment shown in Figure 8 of the drawings, one or more of the flanges of the column 17 may be provided with rack teeth, or a separately formed rack member may be secured to the column in any suitable fashion. Such a rack is indicated at 42 and a drive pinion 43 is mounted in suitable bearings fixed adjacent the bottom of the trench and near the top of the well 26. The drive pinion 43 is operatively connected with a suitable source of power by any desired type of transmission gearing.

In Figure 9 of the drawings, a fluid pressure device is shown by means of which the columns 17 may be raised. Each of the well or socket structures 22 is made air or liquid tight depending upon the fluid medium employed. The lower ends of each of the columns 17 are provided with piston portions 45 which fit within the bores of the members 22. Conduits 46 communicate with the lower ends of the members 22 and lead to a valve arrangement which is capable of alternatively connecting the conduits with a suitable source of fluid pressure or venting the conduits to relieve the pressure.

At suitable points along the path of travel of the columns 17, anti-friction guiding shoes or brackets may be disposed; for example, within the wall 26 or along the height of the well or socket member 22. Such a guiding arrangement is shown in Figure 10 of the drawings. The guide shoe is designated generally by the reference numeral 50 and comprises fundamentally the channel piece 51 which is adapted to receive a flange 17A of one of the columns 17. The channel element 51 is braced by means of a vertical plate 52 which may be welded thereto centrally of its outer face and the two short horizontally extending channel sections 53, the edges of the flanges of which are also welded to the outer face of the channel 51. The inner faces of the flanges 55 of the channel 51 and also of the web 56 of this element are grooved to receive the porous metal bearing strips 60 and 61. The strips 60 and 61 are impregnated with a suitable lubricant which is fed thereto through the ducts 63 drilled through the channel 51 and closed at the upper ends by means of the plugs 64. The vertical

edges of the flanges 17A of the columns 17 are adapted to slide against the lubricated inserts 60 carried by the flanges 55 of the guide member, and a vertical strip 65 is secured centrally of the flange 17A so as to slide upon the bearing insert 61 provided on the web of the guide member. The runner strip 65 is preferably made of a rust resisting metal.

The columns 17 at the ends of the closure system adjacent the front walls 67 of the wing sections 12 of the building may be guided throughout their length by the wall edges or jambs as the columns rise. Such an arrangement is shown in Figure 11 of the drawings where the flanges 17A and the web 17B of one of the end columns embraces the projecting edge or jamb portion 68 of the wall 67. Weather strips 69 may be provided to seal the slot between the column flange and the wall of the building.

The means for releasably and rotatably connecting the panel ends with the adjacent columns will now be described with particular reference to Figures 12 to 15, inclusive. At intervals where the panel attaching means occur, the web 17B of each column is perforated as at 70 and upon each face of the web 17B adjacent the opening 70 there are secured, as by welding, the tubular members 71. Within the outwardly projecting open ends of the members 71 there are disposed the bushings 72 and within these bushings is received the bolt 75. Rotatably mounted upon each end of the bolt 75 and retained in position thereon by means of the nuts 76 are the receptacles 77 which are adapted to engage cooperating elements on the ends of the panels 20 when they are to be raised. Each of the receptacle members 77 are provided with inner recesses 78 to receive the nuts 76 applied to the bolt ends, and an outer U-shaped notch or socket portion 80, between which a space 81 is provided, which space is provided with a bottom opening extending all the way through the member 77. This latter feature enables any moisture which might collect within the sockets of the member 77 to drain off. The upper portions of the members 77 are provided with bevelled faces 83 for a purpose which will be presently described. Similarly the lower outer portions of the elements 77 are bevelled as at 84.

Extending diagonally upwardly and downwardly from the member 77, as clearly shown in Figure 13 of the drawings, are the ears 85, these ears preferably extending at angles of 45 degrees from the vertical. The ends of the ears are pivotally connected as by means of the bolts 86 with the pair of elongated vertically disposed actuating rods or strips 90. These actuating rods extend from one end to the other of the posts or columns 17 and are adapted to be operated by suitable mechanism not shown, in order to rotate the receptacles 77 through angles of 90 degrees counterclockwise from the position shown in Figure 13. In other words, the left-hand actuating rods or strips 90 in this figure are in their uppermost position. The outwardly directed faces of the element 77 are provided with a pair of sockets 92.

Each end of the panels 20 is provided with projectible and retractable elements which cooperate with the receptacles 77 carried by the columns. These arrangements are best shown in Figures 12 and 16. Substantially self-contained assemblies or inserts designated generally by the numeral 100 are set in kerfs provided in the ends of the panel members, these insert

structures being secured rigidly in place by means of the bolts 101 which pass through the front plates 102 of the assemblies. Arranged for projection outwardly from the end of the panels at a central point are the headed elements 105, which elements are flanked by a pair of separately projectible and retractible pins 106 the ends of which are preferably tapered to a point. When the panels are joined to the columns and the closure is raised toward closed position the headed projecting element 105 has its shank portion received in the trough-like portion 80 of the element 77 as clearly shown in Figure 12, the head of the element 105 occupying the intermediate space 81. The laterally disposed projecting pins 106 are adapted to enter the holes 92 upon either side of the element 77 and prevent relative rotation of the panel and the element 77. Thus the panels 20 may be rotated from open to closed position when the receptacle elements 77 are turned by means of the rods or strips 90. The arrangement is such that the main supporting projecting elements 105 on each side of a tier of panels are successively thrust outwardly into position to be engaged by the respective receptacles 77 carried by the adjacent rising columns when the weight of the panel next above is lifted from the panel thereunder. Then the receptacle 77 engages the elements 105 and raises the panel from the one next below. As soon as the weight of the panel being lifted is removed from the one next below the locking projections 106 are thrust outwardly to engage the openings 92 in the receptacles 77. The means providing for this successive projection of the interlocking panel carrying elements will now be described.

The inserts or assemblies 100 which are set within the ends of the panels comprise the end plates 102 and 110 which plates may be supplemented by the additional thinner plates 111 as shown in Figures 17 and 18. The intermediate body portion of the insert is comprised by an undulating or crenelated sheet metal structure 112 bent to form two laterally disposed loop or bight portions 114 and a central bight portion 115. The main panel lifting projection 105 is received within the central space within the bight portion 115 and is guided through openings in the front and rear plates 102 and 110. The side bolts or pins 106 are similarly guided in openings in these front and rear plates and occupy the spaces formed by the laterally disposed bights 114 of the metal structure 112. Upper and lower transversely disposed rods 118 and 119 are passed through openings formed in the four vertical side walls of the respective compartments of the frame structure 112. The upper bar or rod 118 serves as a pintle or pivot pin for a sheet metal toggle member 120, the opposite end of which is pivotally connected with the projectible bolt 105 as by means of the pin 121. The toggle member 120 is composed of two hinged inverted trough-like elements 123 and 124, the side walls or flanges of which are perforated to receive the respective pivot pins or rods 118 and 121, and the webs of which are pivotally secured together as by means of the strap 125, this strap being riveted or otherwise suitably secured to the webs 123 and 124 as at 127. The limiting position of the toggle 120 when contracted is determined by the abutment of the wall flanges 122 of the parts 123 and 124 as at 128, all as clearly shown in Figure 17 of the drawings. In this broken position of the toggle

the bolt or projecting element 105 is in its extended position for engagement with the column supported receptacle 77. The bolt 105 is urged toward its projected position by means of the coil spring 130 one end of which is secured upon the cross rod 119 and the opposite end secured to the rearward portion of the projectible bolt 105 as by means of the cotter 132.

Each of the laterally disposed locking pins 106 is adapted to be projected and retracted by similarly constructed toggle devices 135. One of these devices is shown in longitudinal direction in Figure 18 and it will be seen that element 136 has its side flanges perforated to receive the cross rod 119 and the rear half 137 of the toggle has its side walls straddling and pivotally connected with one of the pins 106 by means of the pivot pin 138. The side walls of the box-like toggle elements 136 and 137 abut as at 139 when the toggle is contracted and the pins 106 are projected under the influence of the coil springs 140 which extend between the rods 118 and the cotters 141 which secure them to the rearward portions of the pins 106.

It will be readily understood that when any selected panel 20 rests upon the next lower one the toggles 135 controlling the locking pins 106 are extended longitudinally so that they completely enter the box-like spaces within the bights of the frame structure 112 and thus the pins 106 are retracted. Similarly when an upper panel rests upon the selected panel the weight of the superposed panel forces the toggle 120 into the space within the central bight of the frame 112 of the insert 100 and thus retracts the main supporting pin 105. In this way the columns 17 and their panel supporting mechanism may pass freely up and down along the ends of the panels without disturbing the interlocking elements. However, the upper and lower bevelled portions 83 and 84 provided on the faces of the brackets 77 will serve to wedge the projecting panel carried elements aside if they inadvertently extend too far toward the columns.

If desired, the uppermost panel 20B of the series may be provided with fixed projecting elements which are also in position to be received by the uppermost receptacle 77. Then when the adjacent columns 17 have been raised sufficiently to lift this panel from the one next below the toggle member 120 on the top of the latter panel will rise under the influence of its spring 130 and the lifting bolt 105 of the panel next below will be projected as in the case of the second panel from the top shown in Figure 15. Then the rising receptacle 77 will engage the pin 105 and begin to raise the panel under consideration. As soon as this panel has been lifted a sufficient distance above the panel next below it, the pair of toggle members 135 controlling the locking pins 106 will be permitted to project beyond the bottom face of the panel and the locking pins 106 will be thrust outwardly to engage the openings 92 of the receptacles 77, thus securely locking the panels to the lifting mechanism carried by the columns. At the same time that the panel is lifted clear from the one below it so that its locking pins 106 are projected, the lifting bolt 105 of the panel next below will also be projected in readiness to be received by the next succeeding receptacle 77. It will be noted that the upper and lower toggles 120 and 135 are staggered, so there will be no interference when the panels are stacked.

Eventually through these successive operations all of the panels will be raised and the upper ends of the columns 17 will be seated in the sockets 29 provided in the overhead structure 13, the lowermost panel 20A providing a floor or sill to cover the empty trench. In the reverse operation in opening the closure structure, as the columns 17 are lowered into the recesses 22, the successive panels 20 will be stripped from the columns within the trench. When a panel is deposited upon the next lower one, the lifting bolts 105 of the lower one will be retracted by the actuation of its toggle 120, while at the same time upward pressure on the toggles 135 of the panel being lowered will be actuated to retract the pins 106 from the holes 92 and permit the bracket 77 to descend from the bolt 105 of the instant panel (the socket 80 in which bolt 105 rests opening upwardly).

Cover plates may be provided as indicated at 113 to keep snow or dirt out of the interior of the assemblies 100 at the portions which are not occupied by the toggles 120.

Then if it is desired to close the panels to prevent access of weather to the interior of the building, the vertical rods or strips 90 are moved in their respective directions as indicated by the arrows in Figure 13, thus rotating the supporting carriers or receptacles 77 and thereby swinging the panels to closed position whereby they are aligned in a vertical plane as suggested in Figure 5 of the drawings. In order to still provide access of light to the building any desired number of the panels 20 may be made of transparent material.

In Figure 21 of the drawings, there is shown one means of automatically rotating the panels to closed position as the upper ends of the columns are fitted into the overhead structure. One or more of the vertical actuating strips 90 on one side of the devices 77 are extended above the upper end of the column 17 so that as the upper end of the column moves into abutment with the superstructure 13, the rods or strips 90 will be moved downwardly by contact with an abutment surface on the structure 13 and thus automatically rotate the panels to closed position as the upper ends of the columns are moved home. This is an optional feature of the invention which may be employed in certain constructions if desired.

It will be understood that various changes and modifications may be made in the embodiments illustrated and described herein without departing from the scope of the invention as determined by the appended claims.

Having described the invention what is claimed as new and desired to be secured by Letters Patent is:

1. A closure installation for wide openings in buildings such as aircraft hangars and the like, which comprises, in combination, a plurality of displaceable vertical columns disposed at intervals along the width of said opening, the columns thus dividing said opening into a horizontally aligned series of sections, and a vertical tier of horizontally elongated but relatively narrow panels in each of said sections, each panel being individually supported at its ends by adjacent columns.

2. A closure installation for wide openings in buildings such as aircraft hangars and the like, which comprises, in combination, a plurality of displaceable vertical columns disposed at intervals along the width of said opening, the columns thus dividing said openings into a horizontally aligned series of sections, and a vertical tier of

panels in each of said sections, each panel being individually and detachably supported at its ends by adjacent columns.

3. A closure installation for wide openings in buildings such as aircraft hangars and the like, which comprises, in combination, a plurality of vertical columns disposed at intervals along the width of said opening, the columns thus dividing said opening into a horizontally aligned series of sections, a vertical tier of horizontally elongated but relatively narrow panels in each of said sections, each panel being individually supported at its ends by adjacent columns and means connected with the ends of said panels for rotating said panels from horizontal to vertical positions wherein they are aligned in a vertical plane and vice versa, the vertical spacing of the panels being approximately equal to the transverse width of a panel, whereby the edges of adjacent panels substantially contact when they are in a vertical plane thus completely closing the closure.

4. A closure installation for wide openings in buildings such as aircraft hangars and the like, which comprises, in combination, a plurality of vertical columns disposed at intervals along the width of said opening, the columns thus dividing said opening into a horizontally aligned series of sections, a vertical tier of panels in each of said sections, each panel being individually supported at its ends by adjacent columns, vertically elongated recesses at spaced points along the threshold of said opening for receiving said columns to open the closure, and means for raising and lowering said columns from and to positions within said recesses and across said opening.

5. A closure installation for wide openings in buildings such as aircraft hangars and the like, which comprises, in combination, a plurality of vertical columns disposed at intervals along the width of said opening, the columns thus dividing said opening into a horizontally aligned series of sections, a vertical tier of panels in each of said sections, each panel being individually supported at its ends by adjacent columns, vertically elongated recesses at spaced points along the threshold of said opening for receiving said columns to open the closure, and means for raising and lowering said columns from and to positions within said recesses and across said opening, columns at the sides of said opening adjacent the jambs thereof and being guided throughout their vertical movement by said jambs.

6. A closure installation for wide openings in buildings such as aircraft hangars and the like, which comprises, in combination, a plurality of vertical columns disposed at intervals along the width of said opening, the columns thus dividing said opening into a horizontally aligned series of sections, a vertical tier of panels in each of said sections, supported at its ends by adjacent columns, vertically elongated recesses at spaced points along the threshold of said opening for receiving said columns to open the closure, and means for raising and lowering said columns from and to positions within said recesses and across said opening, columns at the sides of said opening adjacent the jambs thereof and being guided throughout their vertical movement at said jambs, intermediate columns being guided by anti-friction means on the walls of said recesses.

7. A closure installation for wide openings in buildings such as aircraft hangars and the like, which comprises, in combination, a plurality of vertical columns disposed at intervals along the

width of said opening, the columns thus dividing said opening into a horizontally aligned series of sections, a vertical tier of panels in each of said sections, each panel being individually supported at its ends by adjacent columns, vertically aligned recesses at spaced points along the threshold of said opening for receiving said columns to open the closure, means for raising and lowering said columns from and to positions within said recesses and across said opening, and means at the lintel of said opening for receiving the upper ends of said columns at the end of their upward closing travel and providing horizontal bracing for the closure.

8. A closure installation for wide openings in buildings such as aircraft hangars and the like, which comprises, in combination, a plurality of vertical columns disposed at intervals along the width of said opening, the columns thus dividing said opening into a horizontally aligned series of sections, a vertical tier of panels in each of said sections, each panel being individually and detachably supported at its ends by adjacent columns, vertically elongated recesses at spaced points along the threshold of said opening for receiving said columns to open the closure, means for raising and lowering said columns from and to positions within said recesses and across said opening, and means for automatically successively disconnecting the panel ends from the columns as the panels are stopped adjacent the threshold level as the columns descend and for re-attaching the panel ends to the columns as the latter rise.

9. A closure structure for an opening in a building and the like comprising, in combination, a pair of spaced elongated supporting members, a series of panels disposed between said supporting members, each of said panels being detachably connected at its ends with said members, the means for connecting said panel ends to said members comprising brackets attached to said members at spaced points along their length, and cooperating elements carried by said panel and adapted to interlock with said brackets, recesses in one wall of said opening for receiving said supporting members when longitudinally retracted, means for retracting and projecting said supporting members, means for successively stopping said panels at said wall of the opening when the members are retracted, means for automatically releasing the interengagement of said panels and said members as the members are retracted and the panels stacked against said wall and for automatically effecting reengagement of said panels and members as the latter are again projected across the opening.

10. A closure structure for an opening in a building and the like, comprising, in combination, a pair of spaced vertical columns, a vertical tier of panels disposed between said columns, means for detachably connecting the ends of said panels with said columns at spaced points therealong, recesses in the threshold of said opening to receive said columns, means for retracting said columns into and projecting them from said recesses, said means comprising a power actuated cable drum, cables on said drum each guided into a recess and operatively connected with the lower end of one of said columns, whereby said cables may raise and lower the columns.

11. A closure structure for an opening in a building and the like, comprising in combination a pair of spaced vertical columns, a vertical tier of panels disposed between said columns, means

for detachably connecting the ends of said panels with said columns at spaced points therealong, recesses in the threshold of said opening to receive said columns, means for retracting said columns into and projecting them from said recesses, said means comprising a rack on each of said columns and a pinion meshing with said rack and rotatable in either direction to raise or lower the columns.

12. A closure structure for an opening in a building and the like, comprising, in combination, a pair of spaced vertical columns, a vertical tier of panels disposed between said columns, means for detachably connecting the ends of said panels with said columns at spaced points therealong, recesses in the threshold of said opening to receive said columns, means for retracting said columns into and projecting them from said recesses, said means comprising a piston on each of said columns and fitting the wall of the associated recess, the bottoms of said recesses being closed, and means for admitting fluid pressure to and exhausting it from the recesses below said pistons to raise and lower the columns.

13. A closure structure for an opening in a building and the like, comprising, in combination, a pair of spaced vertical columns, a vertical tier of panels disposed between said columns, means for detachably connecting the ends of said panels with said columns at spaced points therealong, recesses in the threshold of said opening to receive said columns, means for retracting said columns into and projecting them from said recesses, a trench provided along said threshold to receive the panels, means for automatically and successively disconnecting said panel ends from the columns as the panels are stopped adjacent the bottom of said trench as the columns are retracted into said recesses and for automatically re-engaging the panel ends with the columns as the latter rise.

14. A closure structure for an opening in a building and the like, comprising, in combination, a pair of spaced vertical columns, a vertical tier of panels disposed between said columns, means for detachably connecting the ends of said panels with the respective columns at spaced points therealong, recesses in the threshold of said opening to receive said columns, means for retracting said columns into and projecting them from said recesses, a trench provided along said threshold to receive the panels, means for automatically and successively disconnecting said panel ends from the columns as the panels are stopped adjacent the bottom of said trench as the columns are retracted into said recesses, and for automatically re-engaging the panel ends with the columns as the latter rise, the trench being of a depth to exactly accommodate all of the panels, the uppermost panel when the closure is collapsed providing a sill for the opening.

15. A closure structure for an opening in a building and the like, comprising, in combination, a pair of spaced vertical columns, a vertical tier of panels disposed between said columns, means for detachably connecting the ends of said panels with the respective columns at spaced points therealong, recesses in the threshold of said opening to receive said columns, means for retracting said columns into and projecting them from said recesses, a trench provided along said threshold to receive the panels, means for automatically and successively dis-

connecting said panel ends from the columns as the panels are stopped adjacent the bottom of said trench as the columns are retracted into said recesses, and for automatically re-engaging the panel ends with the columns as the latter rise, the trench being of a depth to exactly accommodate all of the panels, the uppermost panel when the closure is collapsed providing a sill for the opening, and the lowermost panel providing a closure for the trench itself when the main closure is fully extended.

16. A closure structure for an opening in a building and the like, comprising, in combination, a pair of spaced vertical columns, a vertical tier of panels disposed between said columns, means for detachably connecting the ends of said panels with said columns at spaced points therealong, recesses in the threshold of said opening to receive said columns, means for retracting said columns into and projecting them from said recesses, a trench provided along said threshold to receive the panels, means for automatically and successively disconnecting said panel ends from the columns as the panels are stopped adjacent the bottom of said trench as the columns are retracted into said recesses, and for automatically re-engaging the panel ends with the columns as the latter rise, the lowermost panel providing a closure for the trench itself when the main closure is fully extended, and means for rotating certain of said panels from horizontal to vertical positions and vice versa, said lowermost panel however, being non-rotatable.

17. A closure structure for an opening in a building and the like, comprising, in combination, a pair of spaced vertical columns, a vertical tier of panels disposed between said columns, means for detachably connecting the ends of said panels with said columns at spaced points therealong, recesses in the threshold of said opening to receive said columns, means for retracting said columns into and projecting them from said recesses, a trench provided along said threshold to receive the panels, means for automatically and successively disconnecting said panel ends from the columns as the panels are stopped adjacent the bottom of said trench as the columns are retracted into said recesses, and for automatically re-engaging the panel ends with the columns as the latter rise, means for rotating certain of said panels from horizontal to vertical positions, and means for automatically actuating said last named means upon contact of said column with the lintel of said opening.

18. A closure for an opening in a building and the like, wherein a recess is formed in the threshold of said opening; said closure comprising, in combination, a supporting frame adapted to be projected vertically across said opening and to be retracted downwardly into said recess, a plurality of superposed panels adapted to be carried by said frame and to extend across at least a portion of said opening, supporting brackets for said panels carried by said frame at spaced points along its vertical extent, and cooperating elements carried by said panels and respectively adapted to interlock with said brackets, the panels being stripped from said frame as the latter is retracted into said recess downwardly beyond the threshold, and means for automatically releasing the inter-engagement of said interlocking elements as the successive panels are stopped at the threshold, and for automatically re-engag-

ing them as the frame rises and the successive brackets meet their corresponding panels.

19. A closure for an opening in a building and the like, wherein a recess is formed in the threshold of said opening; said closure comprising, in combination, a supporting frame adapted to be projected vertically across said opening and to be retracted downwardly into said recess, a plurality of superposed panels adapted to be carried by said frame and to extend across at least a portion of said opening, supporting brackets for said panels carried by said frame at spaced points along its vertical extent, and cooperating elements carried by said panels and respectively adapted to interlock with said brackets, the panels being stripped from said frame as the latter is retracted into said recess downwardly beyond the threshold, and means for automatically releasing the interengagement of said interlocking elements as the successive panels are stopped and stacked at the threshold, and for automatically re-engaging them as the frame rises and the successive brackets meet their corresponding panels, said automatic means being actuated by the contact and separation of one panel from an adjacent panel during piling and unpiling at the threshold.

20. A closure for an opening in a building and the like, wherein a recess is formed in the threshold of said opening; said closure comprising, in combination, a supporting frame adapted to be projected vertically across said opening and to be retracted downwardly into said recess, a plurality of superposed panels adapted to be carried by said frame and to extend across at least a portion of said opening, supporting brackets for said panels carried by said frame at spaced points along its vertical extent, and cooperating elements carried by said panels and respectively adapted to be projected from said panels and interlock with said brackets, the panels being stripped from said frame as the latter is retracted into recess downwardly beyond the threshold, and means actuated by contact and separation of adjacent panels for automatically projecting the panel carried elements into engagement with the brackets on the associated column and withdrawing them therefrom as the panels are stripped from the columns.

21. A closure for an opening in a building and the like, wherein a recess is formed in the threshold of said opening; said closure comprising, in combination, a supporting frame adapted to be projected vertically across said opening and to be retracted downwardly into said recess, a plurality of superposed panels adapted to be carried by said frame and to extend across at least a portion of said opening, supporting brackets for said panels carried by said frame at spaced points along its vertical extent, and a plurality of cooperating elements carried by said panels and respectively adapted to interlock with said brackets, the panels being stripped from said frame as the latter is retracted into said recess downwardly upon the threshold, said brackets each having an upwardly opening socket thereon adapted to receive one of the panel carrying elements to lift the panel from the one next below, a laterally opening socket in said bracket to receive another of said panel carrying elements to lock the panel to the bracket, means actuated by the removal of a higher panel of the stack for projecting the first named lifting elements and means actuated by the lifting of the instant

panel from the one below for projecting the second named locking element.

22. A closure for an opening in a building and the like, wherein a recess is formed in the threshold of said opening; said closure comprising, in combination, a supporting frame adapted to be projected vertically across said opening and to be retracted downwardly into said recess, a plurality of superposed panels adapted to be carried by said frame and to extend across at least a portion of said opening, supporting brackets for said panels carried by said frame at spaced points along its vertical extent, and cooperating elements carried by said panels and respectively adapted to interlock with said brackets, the panels being stripped from said frame as the latter is retracted into said recess downwardly upon the threshold, said brackets each having an upwardly opening socket thereon adapted to receive one of the projected panel carrying elements to lift the panel from the one next below, a laterally opening socket in said bracket to receive another of said panel carried elements to lock the panel to the bracket, means actuated by the removal of a higher panel of the stack for projecting the first named lifting elements and means actuated by the lifting of the instant panel from the one below for projecting the second named locking element and means for rotating said brackets on the columns to swing the panels from the horizontal to aligned positions in a common vertical plane.

23. A closure for an opening in a building and the like, wherein a recess is formed in the threshold of said opening; said closure comprising, in combination, a supporting frame adapted to be projected vertically across said opening and to be retracted downwardly into said recess, a plurality of superposed panels adapted to be carried by said frame and to extend across at least a

- portion of said opening, supporting brackets for said panels carried by said frame at spaced points along its vertical extent, and cooperating elements carried by said panels and respectively adapted to interlock with said brackets, the panels being stripped from said frame as the latter is retracted into said recess downwardly beyond the threshold, said brackets having an upwardly opening socket thereon adapted to receive one of the projected panel carrying elements to lift the panel from the one next below, a laterally opening socket in said bracket to receive one of said panel carried elements to lock the panel to the bracket, toggle means actuated by the removal of a higher panel of the stack for projecting the first named lifting elements and toggle means actuated by the lifting of the instant panel from the one below for projecting the second named locking element.
24. A closure for an opening providing access to a building such as an aircraft hangar and the like, which comprises, in combination, a supporting frame adapted to be projected vertically across said opening and to be retracted downwardly beyond the threshold of said opening, a plurality of superposed panels adapted to be carried by said frame and to extend across at least a portion of said opening, means for automatically releasing the interengagement of said panels with said frame as the frame descends beyond the threshold and for automatically re-engaging them as the frame rises, stationary guide members for said frame fixed adjacent the threshold of said opening, said guide members each comprising a bracket adapted to embrace a portion of said frame and provided with inserts of porous material impregnated with a lubricant at points of contact with said frame member.
